UNITED STATES PATENT OFFICE.

WILLIAM T. MAXWELL, OF PITTSBURG, PENNSYLVANIA, ASSIGNOR OF THREE-EIGHTHS
TO GEORGE W. EBERHARDT, OF PITTSBURG, PENNSYLVANIA.

GAS-ENGINE.

No. 878,888.

Specification of Letters Patent.

Patented Feb. 11, 1908.

Application filed March 21, 1906. Serial No. 307,157.

To all whom it may concern:

Be it known that I, WILLIAM T. MAXWELL, a resident of Pittsburg, in the county of Allegheny and State of Pennsylvania, have 5 invented a new and useful Improvement in Gas-Engines; and I do hereby declare the following to be a full, clear, and exact description thereof.

This invention relates to gas or gasolene 10 and similar explosive engines and more especially to engines of this character of the multiple cylinder type.

The object of the invention is to provide means for starting such engines directly by 15 explosions of the fuel in the cylinder and without the necessity of turning or cranking the engine shaft as is necessary with certain types of explosion engines.

Some types of explosive engines such as 20 used extensively on motor vehicles, cannot be started without first turning the main shaft, or cranking the same, as it is called. This is necessary in order to create suction in the cylinders to draw in a charge of fuel, 25 compress the same and explode it. To crank the engine shaft it is necessary for the driver to leave his seat and step to the front of the machine. In case of a muddy road this is very disagreeable. Furthermore there 30 is always danger of the engine kicking back thus throwing the crank violently backward. This has frequently resulted in serious injury to the driver.

My invention is intended to overcome the 35 foregoing difficulties and to make it possible for the driver to start the engine without the necessity of leaving his seat.

Generally stated, the invention comprises a fuel supply, means, such as a hand pump, 40 for forcing a charge of fuel into a cylinder, an indicator to show the condition of the sparking circuit and to locate the cylinder having the active spark plug, and valve mechanism for directing the fuel charge to the cylinder 45 having the active spark plug.

The invention also comprises other details of arrangement, such as a lock for the valve mechanism arranged to hold the valve open and which is automatically disengaged when 50 the fuel pump is operated so as to permit the automatic closing of the valves and prevent the explosion from firing back to the fuel supply tank.

The invention also comprises other features

of construction and arrangement hereinafter 55 described and claimed.

In the accompanying drawings Figure 1 is a vertical section through a 4-cylinder engine showing my invention applied thereto; Fig. 2 is a transverse vertical section through the 60 same; Fig. 3 is a detail on an enlarged scale of the cut-off and check valve arrangement for each cylinder; Fig. 4 is a section on an enlarged scale of the valve for directing the fuel to the several cylinders and the operating means therefor; Fig. 5 is an outside view of the same valve; Fig. 6 shows one of the 65 dials; and Fig. 7 is an elevation illustrating a modification.

My invention can be applied to any multiple cylinder explosive engine and the drawings show the same applied to a 4-cylinder gasolene engine such as is used on motor vehicles. This engine is provided with the vertical cylinders 1 2 3 and 4 each of which 70 contains the usual piston 5 having connecting rods 6 leading to cranks 7 on the main drive shaft 8. These cylinders will be provided with the usual inlet 9 and exhaust 10 for the fuel and waste gases, and with a spark 75 plug 11 or other igniter of approved type, and will further have all of the accessories usual with engines of this character. As these form no part of the present invention they are not described nor specifically illustrated. 80 In engines of this character the charges in the several cylinders are exploded in succession, this being accomplished by providing a suitable circuit changer or distributor which directs the current to the 85 spark plugs of the several cylinders in the required sequence. In the drawings such circuit changer is illustrated generally at 12, being actuated by a shaft 13 connected by bevel gears to a counter shaft 14 which is 90 driven from the main shaft by gearing 15. This circuit changer operates in the usual way and needs no further description or 95 illustration.

All of the parts so far described are or may 100 be of the usual construction. My invention consists in adding to the usual connections and appurtenances of such engines the parts now to be described.

Connected to the several cylinders are supplemental fuel supply pipes 16, 17, 18 and 19 105 which lead to a valve 20 arranged to open communication between a fuel supply, such

as a tank 21, and any one of the several cylinders. To force the supply of fuel into these cylinders I provide any suitable means, such as the hand pump 22, foot pump, bulb, or the like, connected between the fuel tank 21 and the valve 20. An air inlet 23 is provided for supplying the proper amount of air to give a mixture of the usual proportions. The valve 20 is shown in detail in Fig. 4, being provided on one side with four ports to which the pipes 16, 17, 18 and 19, respectively, are connected, and having on the other side a port 24 to which is connected a pipe coming from the pump 22. The port 24 communicates with a groove or recess 25 cut in the inner face of the casing. The valve plug 26 is provided with a port 27 which establishes communication between the recess 25 and any one of the several pipes 16, 17, 18 and 19, depending upon the position to which the valve has been turned. This valve may be operated by various means. As shown in the drawings, the valve plug is provided outside of the casing 25 with a pinion 29 which is engaged by a toothed segment 30 on a lever 31. The operating mechanism comprises a suitable bar or rod 33 mounted to both reciprocate and rotate. This bar is provided with four lugs 30 or projections 34, 35, 36 and 37, set 90 degrees from each other and located in different positions lengthwise of the rod. One of these lugs corresponds to each one of the ports 16, 17, 18 and 19 of the valve. The 35 rod has a fixed amplitude of travel being limited in its endwise movement by the collar 38 adapted to come in contact with the casing 39. The rod will first be rotated to bring the desired lug into line with the end of the lever 31 and then by moving the rod lengthwise the lever will be moved and through the same the valve 26 rotates. Inasmuch as the several lugs are located in different positions lengthwise of the rod it is 40 obvious that the valve 26 will be rotated different degrees by the several lugs, thus establishing connection with the different pipes 16, 17, 18 and 19. The valve is returned to its neutral or cut off position, 45 shown in Fig. 4, by the collar 38, which on backward movement of the rod contacts with the lever 31. The rod 33 is retracted automatically, as by means of a spring 40 connected to the end thereof and to a suitable 50 bracket 41. At its forward end the rod is provided with a suitable grip or handle 42 and this handle may serve as an indicating device to determine which one of the several lugs on the rod is in line with the lever 31. 55 For instance when the grip or handle is pointing downwardly the lug 34 will be in line with the lever; when said handle points to the right the lug 35 will be in line with the lever; when said handle points toward the 60 left the lug 36 will be in this position, and

when the handle points upwardly the lug 37 will be in this position. It is preferred, however, to provide the rod with an indicating hand 43 moving over a suitably numbered dial 44, as shown in Fig. 6. Each of the 70 pipes 16, 17, 18 and 19 is also provided with a cutout valve 45 which may be an ordinary 75 2-way cock having connected thereto a lever 46 having a pin and slot connection with a 80 collar or sleeve 47 within which the rod 33 is rotatable. The object of these cutout valves is to close the several pipes close to the cylinders so as to prevent back firing, and also 85 avoid clearance into which the explosion may expand. As an additional precaution 90 each of these pipes is also preferably provided with a check valve of suitable construction, such as shown at 48, said check valve seating toward the fuel supply and closing automatically whenever pressure 95 exists in the cylinder. This check valve will prevent back firing even in case the cutoff valves 45 should be open.

The circuit changer 12, as above stated, directs the current to the spark plugs of the 90 several cylinders in succession, or proper sequence, and the valve 20 is arranged to admit a charge of fuel to the particular cylinder whose spark plug is active at the time it is desired to start the engine. The valve mechanism described will effect this by first turning the rod 33 to the proper position and then moving it longitudinally thus insuring that the charge goes into the cylinder having the active spark plug. In order that the driver 100 may be advised as to which cylinder has the active spark plug, I provide a suitable indicator operated from, or at least in unison with, the circuit changer 12. In the drawing this indicator is shown at 50. This may be 105 an ordinary dial having an indicating hand traveling over the same, which hand is operated by a shaft 51 having a universal joint connection 52 with the circuit changer itself so that the hand of the indicator is rotated 110 in unison with the circuit changer. The points of designation on the dial of the indicator will of course correspond to the spark sections of the circuit changer, so that when the commutator stops in any given position 115 the indicator discloses which cylinder has the active spark plug. The driver will then turn the rod 33 to the corresponding position and then pull out on the handle moving the rod 33 longitudinally to turn the valve 20 to 120 open communication between the pump and the particular cylinder having the active spark plug. He will then operate the pump to force a charge into that cylinder.

Preferably means are provided for holding 125 the valve 20 open until the pump has been fully actuated and then the valve is automatically closed. This is accomplished by providing the rod 33 with a groove or notch 54 into which a spring dog 55 snaps when the 130

rod is fully drawn out, this dog serving to lock the bar in its outermost position and holding the several valves open. The spring dog 55 has a loop 56 which embraces the operating rod 57 of the pump. Said rod is provided with a cam portion 58 which will disengage the dog and release the rod 33 whenever the pump piston is forced fully inwardly. Consequently injection of a charge into the cylinder automatically unlocks the rod 33 and permits the spring 40 to draw the same backwardly, thereby closing all of the valves. If an explosion does not occur as soon as a charge is forced into the cylinder the driver 10 need only move the spark lever which is found on every machine in order to effect the explosion. This explosion will give the main shaft one or more rotations so that the several pistons will then automatically draw 15 in their several charges through the main supply inlets, compress the same and explode them in succession, the circuit changer of course having commenced to rotate as soon as the main shaft commenced to turn.

20 A carbureter of approved type is indicated at 60, having the usual connections to the engine and having connected thereto the usual constant level gasolene tank 61. When an engine has been idle for some time it is 25 necessary to force gasolene from the tank 61 in order to overflow the carbureter and provide a charge which can be drawn into the cylinder by the piston. Heretofore this has been accomplished by connecting a bulb to 30 the tank 61. I provide automatic means for this purpose. To this end the tank 61 has connected thereto a small pump 63, preferably mounted to swing as shown, and arranged to be operated by the retraction of 35 the rod 33. As shown, its piston rod 64 is connected to one of the levers 46. Consequently when the rod 33 is retracted by the spring 40 the pump is actuated to force gasolene from the tank 61 into the carbureter, 40 thus supplying a charge which will be drawn into the cylinder on the first movement of its piston.

45 The operation of the devices described will be readily understood from the foregoing description. The several attachments and connections described are entirely independent of the ordinary supply inlets and exhausts of the cylinders and the operation of all of the other parts on the engine are in no 50 manner interfered with by these attachments. Obviously when the engine is standing still the spark plug of some one of the cylinders will be active. The particular cylinder having the active plug can be readily determined from the indicator 50. Consequently it is only necessary for the driver to first turn the handle 43 to the corresponding position, then pull outwardly on said handle thus moving the rod 33 longitudinally. 55 Whichever one of the several projections 34,

35, 36 or 37 happens to be in line with the lever 31 will engage the same and through the same rotate the valve 20 thus opening communication between the supply pipe 24 and the pipe leading to the cylinder having 60 the active spark plug. Before manipulating the handle 43, or simultaneously therewith, the operator will have drawn the piston of the pump outwardly thus drawing a charge of fuel from the tank and air into the barrel 65 of the pump. As soon as the handle 43 has been pulled forward to its full extent the dog 55 automatically locks the same, thus holding the several valves open. Then the operator forces the pump piston inwardly 70 thereby injecting a charge of fuel into the desired cylinder. As soon as the piston is pushed fully inwardly the dog 55 is withdrawn and the spring 40 retracts the rod 33 thereby automatically closing all of the 75 valves, and simultaneously overflowing the carbureter. In this condition one of the cylinders contains a charge of compressed fuel and all of the connections to the supplemental fuel supply are closed so that the 80 engine is in exactly the same condition that it would be if these supplemental connections were not attached. When the explosion is effected by operation of the usual spark lever the engine begins to operate and thereafter 85 draws in its fuel supply by suction in the ordinary way and explodes the same automatically.

90 Since the attachment does not interfere with the ordinary operation of the engine 100 and does not necessitate any change in the usual mechanism of the engine parts the device can be adapted to any type of multiple cylinder explosive engines.

95 In place of the pump 22 I can use an ordinary bulb, such as used on atomizers, which 105 obviously is a pump. Fig. 7 shows an arrangement adapted for the use of gases instead of a liquid fuel. In this case the tank 21^a is adapted to contain a charge of compressed gas. This tank is connected to a measuring chamber 65 through a suitable valve 66. The measuring chamber 65 has connected thereto a pressure gage 67. In this modification the valve 66 is opened to 110 allow gas to pass into the measuring chamber 65 until the gage 67 shows the desired pressure. The valve 66 is then closed, after which the valve 20 is opened and the fuel gas by its own pressure rushes into the desired 115 cylinder and is exploded therein.

120

What I claim is:

1. A starting arrangement for gas engines comprising in combination a plurality of cylinders, a spark plug in each cylinder, a circuit changer for directing the current to said plugs in succession, an indicator to show the active plug, a fuel supply connected to each cylinder, and valve mechanism and indicator therefor arranged to establish connections from the 125
- 130

- fuel supply to the cylinder having the active spark plug.
2. A starting arrangement for gas engines comprising in combination a plurality of cylinders, an igniter in each cylinder; means for rendering said igniters active in succession, an indicator to show the active igniter, a fuel supply connected to said cylinders, hand operated means for forcing a charge into the cylinders, valve mechanism arranged to establish connection between the fuel supply and the cylinder having the active spark plug, means for locking said valve mechanism open, and means controlled by the hand operated forcing means for automatically closing said valve mechanism.
3. A starting arrangement for gas engines comprising in combination a plurality of cylinders, an igniter for each cylinder, mechanism for rendering said igniters active in succession, a fuel supply, connections therefrom to each of said cylinders, valve mechanism arranged to establish connections from the fuel supply to all of said cylinders, an operating member for said valve mechanism arranged to open connection to only one of said cylinders at a time, and means for automatically closing said valve mechanism.
4. A starting arrangement for gas engines comprising in combination a plurality of cylinders, an igniter for each cylinder, mechanism for rendering said igniters active in succession, a fuel supply, valve mechanism arranged to establish connections between the fuel supply and all of said cylinders, and a shiftable operating member for said valve mechanism provided with a separate connector to the valve mechanism for each of said cylinders and arranged to operate the valve mechanism to open connection to only one cylinder at a time.
5. A starting arrangement for gas engines comprising in combination a plurality of cylinders, an igniter for each cylinder, means for rendering said igniters active in succession, a fuel supply, valve mechanism arranged to establish connection from the fuel supply to each of the cylinders but only one at a time, means for locking said valve mechanism with the valve open, means for forcing a charge of fuel through the valve mechanism, connections therefrom for releasing the lock, and means for automatically closing the valve mechanism.
6. A starting arrangement for gas engines comprising in combination a plurality of cylinders, a spark plug in each cylinder, a circuit changer for directing the current to said spark plugs in succession, an indicator to show the active plug, a fuel supply connected to each cylinder, valve mechanism arranged to establish connections from the fuel supply to the cylinder having an active spark plug, means for locking said valve mechanism with the valve open, hand operated means for forcing a charge of fuel through said connections, and means controlled by said hand operated means for releasing the lock and automatically closing the valve.
7. A starting arrangement for gas engines comprising in combination a plurality of cylinders, an igniter for each cylinder, mechanism for rendering said igniters active in succession, an indicator to show the active spark plug, a fuel supply and pump, connections therefrom to each of said cylinders, valve mechanism arranged to establish connections to each cylinder and including a cutoff for each cylinder, an operating member for said valve mechanism arranged to open connection from the fuel supply to the cylinder having an active spark plug and to open the cutoff valve, means for automatically closing said valves, and a lock for the operating member arranged to hold the valves open and arranged to be released by the pump.
8. A starting arrangement for gas engines comprising in combination a plurality of cylinders, a spark plug for each cylinder, a circuit changer for directing the current to said plugs in succession, an indicator operated in unison with said circuit changer, a fuel supply and pump, connections therefrom to each of said cylinders, valve mechanism arranged to establish connections to each of said cylinders, means for locking said valve mechanism in open position and arranged to be released by the pump operating means, and means for automatically closing said valves.
9. A starting arrangement for gas engines comprising in combination a plurality of cylinders, a spark plug for each cylinder, a circuit changer for directing the current to said plugs in succession, an indicator to show the active spark plug, a fuel supply and pump and connections therefrom to each cylinder, valve mechanism in said connections arranged to establish communication between the fuel supply and each cylinder, operating means for said valve mechanism, an indicator to show the cylinder to which connection is made, a lock for holding said valve mechanism open and arranged to be released by the pump operating means, and means for automatically closing said valve mechanism.
10. A starting arrangement for gas engines comprising in combination a plurality of cylinders, an igniter for each cylinder, means for rendering said igniters active in succession, an indicator to show the active spark plug, a fuel supply connected to each of said cylinders, valve mechanism in said connections arranged to establish communication between the fuel supply and any one of the cylinders, hand operating means for said valve mechanism, and an indicator to show to which cylinder connections are made.
11. A starting arrangement for gas engines comprising in combination a plurality of cylinders, a spark plug for each cylinder, a cir-

cuit changer for directing the current to said plugs in succession, an indicator operated in unison with said circuit changer, a fuel supply and connections therefrom to each of the 5 cylinders, valve mechanism arranged to establish communication between the fuel supply and any one cylinder, operating means for said valve mechanism provided with an indicator by which to set said operating means, and an independent connector for 10 each cylinder between the operating means and the valve mechanism.

12. A starting arrangement for gas engines comprising in combination a plurality of cylinders, a spark plug in each cylinder, a circuit changer for directing the current to said spark plugs in succession, an indicator operated in unison with the circuit changer, a fuel supply and connections therefrom to 15 each of the cylinders, a valve in said connections arranged to establish communication between the fuel supply and any one of the cylinders, a reciprocating rotatable operating rod provided with an independent connection with the valve for each cylinder, and an indicator for setting said operating rod. 20

13. A starting arrangement for multiple cylinder gas engines comprising in combination a plurality of cylinders, an igniter for each 25 cylinder, means for rendering said igniters active in succession, an indicator to show which igniter is active, a fuel supply connection to the cylinders, valve mechanism arranged to establish connection between the fuel supply and the cylinder having the active igniter, operating means for said valve 30 mechanism, a carbureter, and automatically acting means for overflowing said carbureter.

40 14. A starting arrangement for multiple cylinder gas engines comprising in combination, a plurality of cylinders, an igniter for each

cylinder, means for rendering said igniters active in succession, valve mechanism for supplying fuel to said cylinders, means 45 for automatically closing said valve mechanism, a carbureter, and means actuated automatically from said closing means for overflowing said carbureter.

15. A starting arrangement for multiple cylinder gas engines comprising in combination a plurality of cylinders, an igniter for each cylinder, means for rendering said igniters active in succession, an indicator to show which igniter is active, a fuel supply connection to the cylinders, valve mechanism arranged to establish connection between the fuel supply and the cylinder having the active igniter, means for automatically closing 50 said valve mechanism, a carbureter, and 60 means actuated automatically from said closing means for overflowing said carbureter.

16. A starting arrangement for multiple cylinder gas engines comprising in combination a plurality of cylinders, an igniter for each cylinder, means for rendering said igniters active in succession, an indicator to show which igniter is active, a fuel supply 65 connection to the cylinders, valve mechanism arranged to establish connection between the fuel supply and the cylinder having the active igniter, means for automatically closing 70 said valve mechanism, a carbureter, a tank connected thereto, and forcing 75 means operated from said closing means and arranged to force fuel from the tank into the carbureter.

In testimony whereof, I the said WILLIAM T. MAXWELL have hereunto set my hand.

WILLIAM T. MAXWELL.
